ABSTRACT OF THE DISCLOSURE

The equipment includes a bench equipped with means for gripping a cable at a certain distance from one of its ends, and with means for the compression of part of the cable between its end and its gripped part and two shells the internal forms which match the forms of the two bosses to be formed on the cable, and by an intermediate sleeve dismantleable into several parts, the internal diameter of which is equal to the diameter of the cable and the length of which is substantially equal to the distance between the two bosses to be formed. By the setting in action of the compression means the gripped cable is compelled to distend into the two shells fitted thereon, while the portion thereof received in the intermediate sleeve placed between the two shells retains its original diameter.

SUMMARY OF THE INVENTION

This invention relates to the construction of equipment for the formation of double bosses on prestressing cables for reinforced concrete work, namely a traction boss formed following an anchoring boss.

The equipment according to the invention is noteworthy in that it is constituted on the one hand by a bench equipped with means for gripping a cable at a certain distance from one of its ends, and with means for compression of the part of the cable between its end and its gripped part, and on the other hand by two shells the internal forms of which match the forms of the two bosses to be formed on the cable, and by intermediate sleeve dismantleable into several parts, the internal diameter of which is equal to the diameter of the cable and the length of which is substantially equal to the distance between the two bosses to be formed. The engagement is such that by the setting in action of the compression means the gripped cable is compelled to distend into the two shells, while its part received in the intermediate sleeve placed between the two shells retains its original diameter, therefore the bosses are stabilized by pouring mortar or other appropriate product into the shells and is permitted to set the mortar before the cable equipped with its two shells enclosing the bosses is withdrawn from the bench and the intermediate sleeve is removed.

The invention has at least one of the following characteristics:

(a) The bench is in the form of a box of elongated form, one end wall of which forms a bearing face for the means for gripping the cable, while its opposite end wall forms the bearing face for a hydraulic jack for compression of the said cable.

(b) The bottom of the box is equipped with centering supports for the shells and the intermediate sleeve.

(c) The intermediate sleeve is supported by a carriage mounted for longitudinal sliding in the bench, preferably in two slideways formed in the longitudinal walls of the said bench.

(d) A lower half-sleeve is rigidly fixed on the carrier

2

and an upper half-sleeve is hingedly mounted thereon and equipped with means for tightening it against the lower half-sleeve.

(e) The means for gripping the cable consist of an assembly of wedges or jaws having a common cylindrical bore the external faces of which possess a certain slope, and which are in contact with the internal faces of similar slope of a guide intended to bear against an internal end face of the bench.

(f) The guide of the wedges is in several parts received in a cylindrical bore of an anchoring piece immobilised not only translationally but also rotationally in the bench.

(g) The device for gripping the cable at a predetermined distance from its end can also be constituted by two half vice-jaws gripped by high-strength bolts.

(h) Between the jack and the end of the cable a thrust piece is disposed which is guided axially in the bench and comprises a ferrule for reception of the end of the said cable.

(i) The thrust piece is equipped with a screw or other locking element adapted to keep the cable under compression after release and removal of the jack, for the purpose of the casting of the mortar, or other appropriate product, for stabilization of the bosses.

The invention will be better understood on reading of the following description and examination of the accompanying drawings which show, by way of example, a form of embodiment of equipment according to the invention for the formation of double bosses on cables for pre-stressing reinforced concrete work.

In these drawings:

FIG. 1 represents diagrammatically, in perspective, the whole of the equipment and the cable end upon which two bosses are to be formed, the intermediate sleeve being assumed to be detached from the bench and the form of the thrust piece being simplified, for reasons of clarity of representation,

FIG. 2 is a plan view of the whole of the equipment in position for an operation of formation of two bosses on a cable end,

FIG. 3 is a vertical section along the line III—III in FIG. 2,

FIG. 4 is a cross-section along the line IV—IV in FIG. 3, and

FIG. 5 is a cross-section along the line V—V in FIG. 3.

For the formation of two bosses, namely an anchoring boss 1 (FIG. 3) and a traction boss 2, on a cable 3 intended for the prestressing of reinforced concrete work, the equipment as represented comprises a special bench designated as a whole by 5 (FIG. 1) and a certain number of special pieces for fitting on the cable.

These special pieces include a set of pieces forming a device for gripping the cable at a predetermined distance from its end. This set is constituted by two wedges 11, 12 which possess a common cylindrical bore, the diameter of which is equal to that of the cable 3 (see also FIGS. 1 and 5). These two wedges leave between them a certain interval in a diametrical plane so that they can grip the cable. Each possesses an inclined face 13, 14 which is in contact with a corresponding respective inclined face 15, 16 pertaining to a guide generally designated 17 and itself constituted by two pieces 17a, 17b which are also separated by a small interval in a diametrical plane. The lateral faces of the two wedges 11 and 12 are applied respectively against the corresponding parallel faces 18a, 19a and 18b, 19b of the two parts of the guide 17.

The guide 17 possesses a cylindrical outer surface lodged in a corresponding cylindrical bore 21 of an anchoring piece 22 and it is equipped with a collar 23 intended to bear against a face of the anchoring piece.

A shell 26 (FIGS. 1 to 3) for the anchoring boss and

a shell 27 for the traction boss possess internal forms matching the forms which the said bosses are to possess. Their cylindrical outer surface presents a diameter smaller than that of the bore 21 of the anchoring piece so that subsequently the latter can be withdrawn by passing it over the shells, after the two bosses have been formed, the guide 17 and the wedges being dismantleable since they are in two parts.

The bench 5 is constituted by an assembly of box form formed from steel plates welded to one another, one of the end plates 31 being intended to serve with its internal face as a bearing surface for the anchoring piece 22, and, so that the cable end equipped with the said anchoring piece may be lowered within the bench, this wall 31 has a slot 32 of width corresponding to the diameter of the cable.

The bottom of the bench is equipped with two cradles 34, 35 of suitable shape, adapted to support the two shells 26, 27 respectively at the correct height.

The two lateral walls 36, 37 of the bench 5 possess two longitudinal slots 38, 39 which serve as slideways for the heads of four screws, such as 41 which is secured to a carriage generally designated by 43 and which is intended to support an intermediate sleeve 44. The sleeve 44 is indicated on the cable 3 of FIG. 1, solely for clarity of representation. In reality the sleeve 44 is formed by a lower half-sleeve 44a which is secured to the carriage 43 and an upper half-sleeve 44b hingedly mounted on the carriage. The sleeve 44 is carried on two levers 48, 49 (see also FIG. 4) pivotably mounted on spindles 51, 52 carried by this carriage. The cable 3 can be gripped between the two half-sleeves by means of two handles 55, 56 respectively. The handles, intended to bear respectively on the tops of the ends of the two levers 48, 49, are screwed into the central part of two caps 57, 58 which are pivotably mounted about horizontal spindles 61, 62 carried by the carriage 43. Locking nuts 63, 64 permit the locking of the handles 55, 56.

In the vicinity of the other end of the bench 5 another carriage 71 can slide, and this carries screws 72, 73 slidably mounted in two horizontal slots 74, 75 serving as slideways for the heads of the said screws. This carriage also slides on two straight strips 68, 69 fixed against the inner faces of the bench and forming slideways. The carriage 71 is equipped with a ferrule 77 the end of which has a hollow 78 of suitable dimensions to receive the preferably suitably whipped end of the cable 3.

In the space between the carriage 71 and the end wall 81 of the bench 5, a hydraulic jack 82 can be received. The jack 82 is (FIG. 1) equipped with two pistons 83, 84 disposed on either side of the central vertical plane of the said jack, so as to come to bear against the adjacent face of the carriage 71 on either side of the geometrical axis of the ferrule 77 and consequently of the cable to be compressed.

Axially of the ferrule 77 there is a blocking screw 86 which screws into the end wall 81 of the bench. This screw is for example equipped with a head 87 pierced with radial holes into which a tommy bar can be introduced to rotate it. The removable jack assembly 82 possesses a central groove 89 in which the blocking screw 86 can be received.

In order to impart rigidity to the assembly and for convenience in handling, the two longitudinal walls of the bench 5 possess two upper flanges 91, 92 situated in one and the same plane.

Finally a horse-shoe-shaped packing piece 94 of variable thickness can be interposed between the intermediate sleeve 44 and the shell 26.

This equipment can be utilised in the following manner:

The anchoring piece 22 is solidly fixed on a cable 3 at a specific distance from its end by means of the wedges 11, 12 and the guides 17a, 17b. Then the anchoring boss

5 shell 26 and the traction boss shell 27 are successively slipped onto the cable.

10 The upper half-sleeve 44b mounted on the carriage 43 of the bench being open, the cable equipped with the above-mentioned parts is lowered into the said bench, so that it rests on the lower half-sleeve 44a and so that the anchoring piece 22 places itself against the internal face of the end wall 31 of the bench. The two shells 26, 27 rest on their respective cradles 34 and 35, while the anchoring piece 22 rests on the support cross-piece 85. As 15 this anchoring piece is of the same width as the bench, it is immobilised in rotation also. The upper half-sleeve 44b is turned down on the cable and tightened by means of the two handles 55, 56. The carriage 71 is brought closer to the traction boss shell 27, it being ensured that the ferrule 77 is well engaged on the end of the cable. The removable jack 82 is put into position abutting against the end face 81 of the bench. This jack is set in action so that the cable parts situated in the two shells are 20 distended, forming the two bosses 1 and 2. The intermediate part of the cable included between these two bosses is unable to distend since it is imprisoned and gripped in the intermediate sleeve 44. When the compression is terminated, the blocking screw 86 is tightened until its end bears against the carriage 71. Thereafter the 25 hydraulic jack 82 can be released and removed from the bench. The assembly comprising the bench and the cable part which it encloses is erected so that the mortar 98, 99 for stabilization of the bosses can be poured into the two shells. When the mortar is sufficiently set, the blocking screw 86 can be released, the sleeve 44 opened and the cable end equipped with its two shells and the anchoring piece assembly 22 can be withdrawn upwards. Then 30 the guide 17 is expelled on the side opposite to the anchoring boss 1, so that the wedges 15 and 16 are released. The wedges and the two halves 17a, 17b of the guide 17 are withdrawn and finally it is then possible to withdraw the anchoring piece 22 itself, by passing it over the two shells 26, 27. The external diameters of the shells 35 26 and 27 are made smaller than the bore 21 of the said anchoring piece for this purpose.

40 Later, when the cable has been placed in position in the prestressed reinforced concrete work and has been placed under its definitive tension, it will be cut through between the two bosses and it will then be possible to recover the traction boss shell 27. A draw taper 8 provided of the shell 27 as indicated at 90 (FIG. 3) to facilitate the removal of the anchoring boss and the stabilizing mortar from the mould.

45 The invention is not of course limited to the form of embodiment as described and represented, modifications can be effected therein without thereby departing from the scope of the invention.

50 Thus for example the device for gripping the cable at a predetermined distance from its end can equally be constituted by two half vice jaws gripped by high-strength bolts.

55 What I claim is:

60 1. An apparatus for forming two bosses on a metal cable used for reinforced concrete, comprising a bench having a box-like shape, means non-rotatably carried by the bench for gripping the cable at a distance from one of its ends, means supported on the bench for compressing the part of the cable between said one end and the gripped part, two shells each having an internal shape corresponding to the shape of the boss to be formed, an intermediate sleeve being separable into at least two parts, said sleeve having an internal diameter being equal to the diameter of the cable and the length thereof being substantially 65 equal to the desired distance between the two bosses to be formed, whereupon actuation of said compressing means causes the cable to be distended into the two shells placed on it while the shape of the part of the cable in the intermediate sleeve is retained in its normal shape, said intermediate sleeve being removable from the cable 70

and the cable being removable from the bench, and means being provided for retaining, at least temporarily, the shells around the bosses after the cable is removed from the bench.

2. An apparatus as claimed in claim 1, wherein the bench is in the form of an elongated box having one end wall forming a bearing face for the means for gripping the cable and an opposite end wall forming a bearing face for the compressing means and wherein the compressing means is a hydraulic jack.

3. An apparatus as claimed in claim 2, having a carriage mounted in two slideways formed in the longitudinal walls of the box, a lower half-sleeve of the intermediate sleeve rigidly mounted on the carriage, an upper half-sleeve hinged to the carriage and means on the carriage for tightening the upper half-sleeve against the lower half-sleeve.

means for gripping the cable comprises a guide having a

4. An apparatus as claimed in claim 1, wherein the tapered bore and a surface engageable with said bearing face, and wedge members together forming a cylindrical bore and having inclined external faces engageable with said tapered bore.

5. An apparatus for forming an anchoring boss and a traction boss on a metal cable used for reinforced concrete comprising an elongated rectangular box forming a bench, a wall at one end of the bench having a U-shaped recess of a width corresponding to the diameter of the cable, an anchoring piece received therein having a width equal to the internal width of the bench and having a cylindrical bore, a two-piece guide received in said anchoring piece having an outer diameter equal to the diameter of the cylindrical bore and having a tapered

internal bore, two wedges received in said guide having inclined external surfaces slideable on the surfaces of the tapered bore and having together an internal bore equal to the diameter of the cable, a first cradle spaced from the wall of the bench for supporting a first shell for the anchoring boss, a second cradle spaced from the first cradle for supporting a second shell for the traction boss, each of said shells having an internal shape of the boss to be formed, a first carriage mounted in two slideways formed in the longitudinal walls of the box, a lower half-sleeve rigidly mounted on the carriage, an upper half-sleeve hinged to the carriage, screw means for tightening the upper half-sleeve on the cable supported by the lower half-sleeve, a second carriage slidably mounted in two longitudinal slots in the longitudinal walls of the box, a hollow ferrule attached to the second carriage for receiving an end of the cable, a hydraulic jack, having two pistons, for fitting between the second carriage and the other end wall of the box; and a blocking screw connected to the second carriage and passing through the hydraulic jack while being threadedly engaged in said other end wall.
